DESIGN FOR A POTATO CHOPPER

Minnie Flood, Morrice, Mich.

Application May 17, 1941, Serial No. 101,002

Term of patent 3½ years

To all whom it may concern:

Be it known that I, Minnie Flood, a citizen of the United States and a resident of Morrice, in the county of Shiawassee in the State of Michigan, have invented a new, original, and ornamental Design for a Potato Chopper, of which the following is a specification, reference being had to the accompanying drawing, forming a part hereof.

I claim:

The ornamental design for a potato chopper, as shown.

MINNIE FLOOD.
